UNITED STATES PATENT OFFICE.

ERNEST J. SWEETLAND, OF MONTCLAIR, NEW JERSEY, ASSIGNOR, BY MESNE ASSIGNMENTS, TO UNITED FILTERS CORPORATION, A CORPORATION OF DELAWARE.

HINGE.

1,237,838.

Specification of Letters Patent. Patented Aug. 21, 1917.

Application filed December 31, 1913. Serial No. 809,619.

To all whom it may concern:

Be it known that I, ERNEST J. SWEETLAND, a citizen of the United States, residing in the town of Montclair, county of Essex, and 5 State of New Jersey, have invented certain new and useful Improvements in Hinges, of which the following is a specification.

My invention relates to a hinge construction, in which the pintle is provided with 10 eccentric portions which are adapted to make the hinge leaves relatively adjustable so as to compensate for wear or for other purposes. Such a hinge is particularly adapted for use in connecting the sections of 15 the casing of a pressure filter of the general type illustrated and described in my prior Patent No. 1,083,305 of January 6th, 1914. In that patent I showed a filter comprising two sections hinged at one side, with tension 20 means on both the hinged side and the free side for forcing the two sections together in order to make a tight joint. My present invention has to do with an improved hinge mechanism whereby the tension-locking 25 means is required on only the free side, that is, the side opposite the hinge.

In the accompanying drawings which form a part of this specification, Figure 1 is an end view of a filter provided with my 30 improved hinge and showing the lower movable section of the casing swung out of its normal position to permit the cleaning of the filter; Fig. 2 is a perspective view on an enlarged scale of the hinge mechanism; Fig. 35 3 is a transverse sectional view on line IV—IV of Fig. 2, Fig. 4 is a longitudinal view on line V—V of Fig. 3. Fig. 5 is a transverse sectional view through the filter.

Referring to the drawings in detail, the 40 numeral 1 designates a base upon which is mounted a pair of standards or uprights 2 which support the fixed section 3 of the casing, being secured thereto by the bolts 4, or in any other suitable manner.

45 The lower section by a suitable number of hinges 18 of the casing is hinged to the upper section. Each hinge comprises an upper leaf 19 securely mounted upon the upper section, and a lower leaf 20 similarly 50 mounted upon the movable section of the casing. The upper leaf may be provided with a pair of integral depending lugs 21, beneath which is received a similar lug 22 forming a part of the lower leaf. The lugs 55 21 are provided with axially alined central

openings 23, and the lug 22 has a similar circular opening 24. A single shaft 25 extends along the entire length of the filter and acts as a pintle for each set of hinge leaves. This shaft comprises circular portions 26 60 having a diameter equal to the diameter of the holes through the lugs of the hinges. Between these portions are portions 27 of reduced circular cross-section which are tangent to the periphery of the larger portion of the shaft along a single line 28. These portions of reduced diameter are of the same width as the lugs 22 and are so arranged upon the shaft or pintle that they will each come between a pair of lugs 21. 70 As a result, it will be seen that the lower or movable section of the casing is hung upon the portions of the shaft or pintle of reduced diameter through the medium of the lugs 22 and their associated portions of 75 the hinge, whereas the remainder of the shaft is supported by the lugs 21. One end of the shaft may be provided with a faceted portion 29 for engagement with a wrench to rotate the shaft, and one or more of the lugs 80 21 may be provided with a set screw 30 passing through the lug and seating on the shaft in order to lock the shaft in any desired position.

This construction of the hinge is designed 85 to compensate for wear upon the packing or gaskets 31 in the abutting edges of the sections of the filter casing. Hitherto it has been thought necessary to provide tensioning means at each side of the casing, as illustrated in my prior patent above referred to, 90 since with tensioning means on only one side of the casing and with a hinge of the ordinary type at the other side, there is no way to prevent leakage at the hinged side of the 95 casing, due to wear in the hinge, and also in the gasket or packing at that side of the casing. When my improved hinge is used, however, it will be observed that the effective axis of the hinge may be readily shifted 100 owing to the eccentricity of that portion of the shaft or pintle upon which the lower or movable section of the casing is hinged. Figs. 3 and 4 illustrate the position of the parts when the structure is new. If, now, 105 there is wear either in the hinge or in the gasket which is adjacent to the hinge, this wear may be compensated for by rotating the shaft or pintle through a small angle. The effect of this rotation will be to raise the 110

axis of the hinge. Since the part of the shaft supporting the movable section of the casing is eccentric with respect to the main axis of the shaft, that is, the axis about which the shaft as a whole must rotate, the amount of wear which may be taken up is equal to the eccentricity or difference in diameter of the large and reduced sections of the shaft. This is obviously true since the lug 22 is always hung upon the topmost element of the reduced portion of the shaft. Therefore, if the parts are initially in the position shown in Figs. 3 and 4, and wear occurs tending to cause leakage along the adjacent line of division between the two casing sections, this wear may be taken up by a slight rotation of the shaft. If the shaft is rotated through 180 degrees from the position shown in Figs. 3 and 4, the result will be that the lower or movable section of the casing is hung from the portion of the shaft section 27 which is tangent to the shaft section of large diameter. In other words, instead of being hung upon the element 32, as shown in Figs. 3 and 4, the lug 22 will rest upon the element 28, and the effective axis of the hinge will have been vertically raised a distance equal to the difference in the diameters of the two shaft sections. It will be seen that providing the hinges with a common pintle not only simplifies the construction, but also makes it possible to adjust the parts simultaneously and uniformly. By making the eccentric portion smaller than the main diameter of the shaft or pintle and causing it to lie within the cylindrical boundary of the latter, there are no outlying projections, and the shaft may be readily slipped through the hinge leaves when the structure is assembled. It is not necessary, however, to use a single unitary pintle in order to achieve many important objects of my invention, and it will be obvious that individual pintles may be used with each set of leaves where deemed desirable.

At the opposite side of the fixed casing from the hinges may be mounted any suitable means for locking the two sections of the casing in operative position, such as the locking bolts illustrated and described in my prior Patent No. 1,083,305. The general operation of the bolts and cam shaft is described in my prior patent referred to.

While I have illustrated and described only one specific embodiment of my device, I realize that it is susceptible of wide variation and I do not desire to be limited to the precise construction shown and described.

Having thus described my invention, I claim:

1. A hinge including a plurality of pairs of leaves, each pair having circular bearing surfaces capable of being placed in register

and a continuous pintle including a cylindrical member of substantially the same diameter as the bearing surfaces engaging the bearing surface in one leaf of each pair and having a plurality of eccentric portions of reduced cross section, each of which supports the second leaf of a pair, the eccentric portions lying within the cylindrical boundary of the body of the pintle. 65 70

2. A hinge including a leaf comprising two separated sections provided with aligned, circular bearing surfaces, a second leaf having a portion adapted to be received between said sections and provided with a circular bearing surface capable of being placed in register with the bearing surfaces of the first leaf, and a pintle including a cylindrical member of substantially the same diameter engaging the bearing surfaces in the first leaf, and having a central eccentric portion of reduced cross-section 80 mounted in the bearing surface of the other 85 leaf. 75

3. A hinge including a leaf comprising two separated sections provided with aligned, circular bearing surfaces, a second leaf having a portion adapted to be received between 90 said sections and provided with a circular bearing surface capable of being placed in register with the bearing surfaces of the first leaf, a pintle including a cylindrical member of substantially the same diameter 95 engaging the bearing surfaces in the first leaf and having a central eccentric portion of reduced cross-section mounted in the bearing surface of the other leaf, and means 100 for preventing the rotation of the pintle with reference to one of the leaves. 100

4. A hinge including a leaf comprising two separated sections provided with aligned, circular bearing surfaces, a second leaf having a portion adapted to be received between 105 said sections and provided with a circular bearing surface capable of being placed in register with the bearing surfaces of the first leaf, and a pintle including a cylindrical member of substantially the same diameter 110 engaging the bearing surfaces in the first leaf, and having a central eccentric portion of reduced cross section mounted in the bearing surface of the other leaf, the axial length of the eccentric portion 115 being slightly greater than the width of the portion of the second leaf which it engages. 110

5. A hinge having its end knuckles bored concentrically, and a pintle, the end portions of which fit said end knuckles, and the intermediate portion of which is eccentric to said end portions. 120
